(57) **CLAIM**

The ornamental design for a lever cover as shown and described.

DESCRIPTION

FIG. 1 is a top perspective view of a lever cover.

FIG. 2 is another top perspective view of the lever cover.

FIG. 3 is a bottom perspective view of the lever cover.

FIG. 4 is another bottom perspective view of the lever cover.

FIG. 5 is still another bottom perspective view of the lever cover.

FIG. 6 is a distal end view of the lever cover.

FIG. 7 is a proximal end view of the lever cover.

FIG. 8 is a left side view of the lever cover.

FIG. 9 is a right side view of the lever cover.

FIG. 10 is a top view of the lever cover; and,

FIG. 11 is a bottom view of the lever cover.

The broken lines in the figures show features of the lever cover that form no part of the claimed design.
